UNITED STATES PATENT OFFICE.

CHARLES EDWARD HAVILAND, OF LIMOGES, FRANCE.

DESIGN FOR A DEEP DISH.

SPECIFICATION forming part of Design No. 17,058, dated January 11, 1887.

Application filed November 20, 1886. Serial No. 219,523. Term of patent 14 years

To all whom it may concern:

Be it known that I, CHARLES EDWARD HAVILAND, a citizen of the United States, residing at Limoges, in the Republic of France, have 5 invented and produced a new and original Design for Deep Dishes, which is described and represented in the following specification and accompanying fac-similes, forming a part of the same.

10 Figure 1 is a perspective view of a dish embodying this design, and Fig. 2 is a diagram showing its horizontal conformations at different heights.

The characteristic features of this design are 15 a body possessing a rectangular form when considered horizontally, with doubly-curved corners, distinguished by an indentation following the line of union between the sides, the said body being bellied and curved to form 20 a bulging main portion, with an outwardly-flaring top and a contracted bottom. The body is gradually contracted from the top or mouth a until a point, b, just below the top is reached, and then is gradually bent outward to form the bulge, as at c, and then curves rather abruptly inwardly to unite with the rectangular foot d. The sides of the body, at their union with each other, have inward bends 6, that produce double curves 5 at the corners.

What I claim is—30 The design for deep dishes, the same consisting of the rectangular body having corners provided with an indentation formed by double curves, a bulging main portion, a flaring top, and a contracted bottom, substantially as shown and described.

35 In testimony whereof I have hereunto set my hand in the presence of two subscribing witnesses.

CH. ED. HAVILAND.
